Fig. 5.

A technical line drawing of a cross-section of a structure. The drawing shows a rectangular frame with a textured, granular interior. A vertical line extends downwards from the top center, and a horizontal line extends to the right from the bottom center. The drawing is labeled 'Fig. 3.' in a cursive script, with the number '28' written above it to its left.

UNITED STATES PATENT OFFICE.

HENRY R. TURNER, OF RIVERSIDE, CALIFORNIA, ASSIGNOR OF ONE-HALF TO
CHARLES NEWEL WAGNER, OF RIVERSIDE, CALIFORNIA.

COMBINATION CHAIR-BED.

Application filed December 28, 1921. Serial No. 525,438.

To all whom it may concern:

Be it known that I, HENRY RIGHTOR TURNER, a citizen of the United States, residing at Riverside, in the county of Riverside, 5 and State of California, have invented certain new and useful Improvements in Combination Chair-Beds, of which the following is a specification, reference being had to the accompanying drawings.

10 It is the purpose of the present invention to utilize two chairs or settees, particularly of the morris-chair type, so connecting them, as to provide a bed for additional sleeping accommodations, the connections being of such 15 a character as to permit the chairs to be easily detached, and used in the daytime to provide seating capacity.

Very often households are overcrowded, and in order to not only provide additional 20 seating capacity, but also additional sleeping accommodations, the invention further aims to provide improved connecting means between reclining chairs, such as the morris type of chair, in order to convert the two 25 chairs into a bed.

In order to accomplish this result the upper end of the back is provided with means to operatively connect with hooks or the like, on the inner faces of the side posts of the 30 front of the chair, when the back of the other chair is lowered, thereby providing a bed.

Still another purpose has to do with providing cut away portions in the end rails of 35 the seat and back of the chair, thereby permitting the occupant of the bed to sleep comfortably and to prevent the occupant from contacting with any obstructions.

A further purpose is the provision of an 40 improved hinge connection between the back and the seat of the chair, so disposed that when the back is lowered and is connected to the front rail of the seat of a second chair, the gap between the cushions of the seat and 45 back is reduced to a minimum, in order to insure comfort for the occupant.

It is the aim to utilize chairs which are 50 relatively wide, such as settees and the like, so that when the back of one chair or settee is lowered and connected to the seat of a second chair, the bed is wide enough to accommodate two occupants. It is obvious 55 that when the back of one chair is lowered and connected to the second chair, and since the forward ends of the arms of one

chair are spaced from the rear ends of the other chair, the provision of means is afforded to permit the occupant to get in the bed from either side, namely between the arms. 60

A still further purpose is the provision of a chair having a compartment below the seat, for the reception of bed clothing, when the chair is utilized in the daytime for seating capacity. 65

Also it is the aim to provide additional side and end rails attachable to the sides of the back of a chair, in connection with additional legs, to support the back when lowered, thereby providing a baby's crib. 70

It will be noted that the adjacent faces of the front posts of the seat of the chair are provided for the reception of one of the baby's crib side rail sections, in alignment with the front posts, for the purpose of closing the front of the seat, while the back is in a perpendicular position, thereby providing a modified form of baby crib. In this latter case the legs of the chair may be supplied with rockers, and in order to permit a chair 80 which includes rockers to be employed in connection with another chair to form a bed, auxiliary legs are applied to the adjacent faces of the rear legs of the chair, adapted to be extended to hold the rocking chair 85 firm.

While the design and construction at present illustrated and set forth are deemed preferable, it is obvious that as a result of a reduction of the invention to a more practical form for commercial purposes, the invention may be susceptible of changes, and the right to these changes is claimed, provided they are comprehended within the scope of what is claimed. 95

The invention comprises further features and combination of parts, as will be herein-after set forth, shown in the drawings and claimed.

In the drawings:—

Figure 1 is a view in perspective of two chairs, showing the back of one connected to the seat of the other, so as to provide a bed;

Figure 2 is an enlarged detail view showing the connection between the upper end of the back and the front of the seat of two chairs; 105

Figure 3 is a sectional view through the connection shown in Figure 2; 110

Figure 4 is an enlarged detail view of the hinge connection between the back and the seat of the chair;

Figure 5 is a sectional view through one of the chairs, to show the compartment under the seat, for the reception of bed clothing, when the chair is utilized for seating capacity;

Figure 6 is a view in perspective of a chair, showing additional side and end rails to be mounted upon the back of the chair when lowered, in order to provide an extension for the side rails or arms of the chair, whereby the chair may be used as a baby's crib;

Figure 7 is a detail view showing the connection between the end rail section 40 and one of the side rail arm rests of a chair;

Figure 8 is a detail view showing the plate 46 to receive the pin 47 carried by the end rail section 40;

Figure 9 is a detail view of a portion of the end rail 40 showing the pin 47;

Figure 10 is a view showing the end rail section 40 mounted on the front of the seat of a chair, which is provided with rockers, so that the chair may be utilized as a cradle; and

Figure 11 is a detail sectional view showing the mounting of the auxiliary leg 49.

Referring to the drawings, 1 designates the chair as a whole, and which comprises the front and rear supporting legs 2 and 3. These legs or posts support a seat, which 35 comprises the side seat pieces 4 and the front and back seat pieces 5 and 6. Below the seat pieces 4, 5 and 6, and also connected to the legs or posts are the side, end and bottom pieces 7, 8 and 9, which are so arranged as to provide a housing or compartment under the seat, for the reception of bed clothing when the chair is utilized for seating capacity.

The rear portions of the side seat pieces 45 have secured to their outer faces by means of screws or the like 10, plates 11.

Each chair includes a back 12, which is capable of being inclined in different positions, or lowered to a horizontal position. 50 The back 12 comprises the longitudinal side strips 13, and the upper and lower end strips 14 and 15. The longitudinal strips 13 are connected by transverse slats 16, to insure rigidity. Secured to the longitudinal 55 side strips 13 of the back by means of screws or the like 17, are plates 18. The plates 11 and 18 have circular extensions 19, which are pivotally united by means of rivets, pins, bolts or the like 20, for the purpose 60 of pivotally supporting the back. It will be noted that the plates 11 and 18 are disposed adjacent the upper portions of the seat pieces 4 and the longitudinal side strips 13, so that when the back is lowered, but a 65 very slight gap is allowed to exist between

the pad or tufted cushions 21 and 22, which are carried by the seat and the back. While tufted cushions or pads are employed in this instance, it is obvious that the seat and back may be provided with the usual bed spring 70 cushions, so that when a chair of this character is coupled to a similar chair, a comfortable bed is provided for additional sleeping accommodations.

The adjacent faces of the front legs or 75 posts 2 of the chair have secured thereto by means of screws or the like 23 the plates 24, which have offset extensions 25, which are designed to enter suitable cavities 26 at the corners of the upper end of the back of a 80 similar chair, that is when the back is lowered, in order to convert two chairs into a bed for sleeping purposes. In order to provide these cavities angular plates 27 are secured by screws or the like 28 to the corners 85 of the upper end of the back. In fact the inner face of the side piece of each plate is outwardly pressed, to cause the reception of the extension 25, when the back is lowered, so that it may be used for sleeping thereon. 90

The front seat piece 5 and the upper end piece 14 of the back is cut away arcuately at 29 and 30, thereby permitting the body of the occupant to sleep comfortably and without coming in contact with any obstruction. While it is not shown, the rear seat piece 6 and the lower end piece 15 of the back 12 are similarly cut away arcuately, so that the body of the occupant may not contact with the rear seat piece or the lower 100 end piece 15 of the back. These particular constructions of seat pieces and end pieces are very substantial, especially for a wide chair, as said pieces warrant additional support to the seat and especially the back, top 105 and bottom thereof, especially when the chair is particularly wide like a settee, or like a wide morris chair.

It is well known morris chairs are old and it is obvious that the idea of the transverse supporting rod for the back of such a chair is also old, and since this is true, it is obvious that other chairs may be utilized for the same purpose as herein disclosed. In other words the morris chair can be built, 110 including the features of construction herein named, for the connecting of the back of one chair to the seat of another, and in addition thereto utilize the transversely disposed supporting rod, so that the back may be 115 reclined in different positions.

However the present embodiment of the invention includes plates 31 secured by screws or the like 32 to the longitudinal side pieces 13 of the back. These plates are provided with sockets 33, which receive the terminals of the spring tensioned bolts 34, which are mounted in the rear ends of the arm rests 35 of the side rails. These spring tensioned bolts are of such a character that 130

when in their normal positions, they engage the sockets 33, to hold the back in a permanent position when used as a cradle. In order to permit the back to be held in different reclining positions, the rear upper portions of the rear supporting legs 3 are provided with racks 33^a having a plurality of bearings 32^a. A rod 31^a may engage any two opposite registering bearings 32^a, the rod engaging in the rear of the back of the chair, in order to hold the back in reclining positions. The rod may engage the extreme lower bearing 32^a, when the back is lowered to a horizontal position, thereby not only reinforcing the back when so disposed, but also providing means to retain the rod from being lost, when the back is in a horizontal position.

The bearings 32^a may be varied in position, according to the reclining positions in which it may be desired to support the back.

Any other suitable, similar means may be employed for supporting the back in various reclining positions. The racks for the transverse supporting rod 31^a extends down upon the rear edge of the rear supporting legs of the chair, in order to permit the rod 31^a to drop down far enough, so as to throw clear the under side of the chair back when lowered, or in order to just engage the under side of the chair back, when lowered to a horizontal position, so as to not only assist in reinforcing the back when lowered, but also permitting the lower part of the racks 35 to constitute containers for the rod when not in use as a reclining support.

When using two chairs similarly constructed, the back of one may be lowered to a horizontal position, and when so lowered, the cavities 26 receive the extensions 25 of the plates 24, and thereby hold the back 12 in alignment with the seats of both chairs. A suitable door 36, which is hingedly mounted at one side of the boxing or housing for the bed clothing, and when lowering the back to a horizontal position, the door may be opened, the bed clothing removed, and applied to the bed, which is made up of two coupled chairs of the morris type, in order to afford additional sleeping accommodations.

It will be noted that the longitudinal side strips 13 of the back, and the upper end piece 14 are provided with plates 37, which are outwardly pressed to provide sockets, which receive extensions 38 of auxiliary side and end rails 39 and 40, that is when the back 12 is lowered to a horizontal position, whereby the chair in this form may be used as a crib. The inner faces of the upper bars 41 of the side rails 39 adjacent the rear ends of the arm rests 35 have plates 42 provided with openings 43, which are designed to receive the spring tensioned bolts 34, to hold the side rails 39 in position. The

cavities or sockets 26 may also receive extensions or tongues 44 of additional legs 45, when the back 12 is lowered to a horizontal position, in order to support the back and hold the same rigid, when the chair is converted into a crib.

It is obvious that the front and rear legs or posts 2 and 3 of the chair, as shown in Figure 8 are provided with rockers 45^a, so that by utilizing the end rail 40 of the crib 75 between the adjacent faces of the upper ends of the legs 2, a baby's cradle may be provided. In other words the morris chair or settee may be converted into a cradle. The end rail 40 when so used is provided with 80 metal extensions 38 to engage sockets 46 on the front seat piece 5 of the chair, while the ends of the end piece 40 have metal extensions 47 to engage slots 48 on the adjacent faces of the front legs or posts 2. By utilizing the end piece 40 in this manner together with the back 12 of the chair, the front and back of the chair is closed, and since the chair is mounted upon rockers, the chair is capable of oscillatory movements, and therefore assures the provision of a suitable cradle.

The end piece 40 of the cradle may be removed, and the chair utilized as a rocking chair. In case it is necessary to connect 95 two rocking chairs, or a single morris chair of the type above set forth to a rocking chair, it is necessary to provide some means to hold the chair rigid. With this in view the adjacent faces of the rear legs or pieces 100 3 of the chair are provided with flat strips or pieces of metal 49 constituting auxiliary legs. These flat pieces or strips of metal are mounted in guides 50, and are held in different adjusted positions by means of the 105 bolts 51. When these strips or pieces of metal are lowered, so that their lower ends may contact with the floor, the chair may be held rigid and against rocking movement.

As previously stated the morris type of chair is an old idea, also the means for holding the back of the chair in reclining positions, therefore it is permissible to utilize a morris type of chair, instead of the form 115 of chair herein disclosed and illustrated.

The present construction of chair is adapted either for the use of cushions or tufted paddings or mattresses, and in providing an expensive chair of this character, 120 suitable coil bed springs may be used, in the seat and the back, so that when the chair is utilized as a part of a bed comfortable sleeping may be afforded.

It is obvious that when two chairs are connected as indicated in Figure 1, the back of the head chair may be lowered, and the crib side and end rails attached, and when this arrangement is used and the chairs are as wide as settees two adults and two children 130

may have sleeping accommodations. Particularly the connection of the two chairs affords an improved combination chair bed.

This arrangement and design of combination chair bed furnishes a very neat, practical and inexpensive piece of furniture very simple in design, and can be manufactured to suit the needs of the various classes.

The invention having been set forth, what is claimed is:—

A combination chair bed, comprising a chair having side arms, a hingedly mounted back, legs detachably connected to the upper portions of the side rails of the back to support the back horizontally when converting the chair into a crib, crib side rail sections

detachably mounted on the side rails of said back, a crib end rail section connecting the crib side rail sections adjacent the top of the back, means connecting the top bars of the 20 crib side rail sections to the arm rests, means comprising angle plates conforming to the corners of the crib side and end rail sections and having flanges engaging the opposite sides thereof, to hold the sections connected 25 at their upper portions, said angle plates having extensions pivoted to the upper bars of the crib side rail sections.

In testimony whereof I hereunto affix my signature.

HENRY R. TURNER.
